tion

Application November 2, 1933, Serial No. 696,362

2 Claims. (Cl. 5—269)

This invention relates to a spring construction.

This invention is an improvement upon the invention shown in the prior Patent No. 1,913,353.

5 In said patent there is broadly disclosed the idea of operatively associating a plurality of coil springs together solely through a small bore helix, the operative association occurring between the serpentine portions of adjacent coils in adjacent 10 rows having a nested relation and encircled by the small bore helix means. As shown in said patent, certain of the coils are of the knotted type—see Fig. 3 thereof. Certain other of the coils are of the unknotted type.

15 The present invention consists of the improvement upon the aforesaid disclosure in that certain turns of an unknotted coil spring are so associated together by a small bore helix, similar to that in the patent in question, whereby the effect 20 of a knotted coil spring is obtained and in a sense, each spring is tied and is thereby the equivalent of a knotted coil spring.

The chief feature of the invention consists in associating a small bore helix with a serpentine 25 like free end of a coil spring, the immediately adjacent portion of the immediately adjacent turn of said spring also being of serpentine formation, each of said serpentine portions consisting of the 30 series of undulations, the adjacent serpentine portions of the same spring being nested together and operatively tied together by said small bore helix, which is operatively associated with a plurality of springs arranged in a row and in spaced 35 relation in the row.

40 In certain types of constructions, particularly in hospital beds, and the like, the spring structure must be capable of flexing when the bed is used for fracture cases. With knotted springs it has been found the knots thereof unduly wear the mattress. With unknotted springs, it has been found the unknotted or free ends have a similar 45 effect only in a more progressive manner.

The present invention contemplates the tying of the springs in such a manner that the mechanical 50 effect or advantage of the knotted spring is obtained, the freedom of the unknotted spring is retained, and the objections to the knotted and unknotted spring structures are eliminated, while the advantages of each are retained.

55 The present invention also incorporates the desired flexibility necessary for the use of the spring structure, incorporating the invention for fracture bed purposes and yet the resulting structure has more rigidity or permanence of construction 60 than that heretofore present in the industry.

As a further feature of the invention, whenever a plurality of independent units are to be associated together, such as disclosed in the Jones Patent No. 1,915,674, each unit comprising a plurality of coil springs arranged in a single row 60 and in spaced relation, this invention readily lends itself to the same, because each spring is the equivalent of a knotted spring and yet is of the unknotted type, and in each unit there must be employed at least two helix means coextensive 65 with the length of the unit and preferably diametrically positioned, although additional helix means may also be employed therewith, if and when desired.

The full nature of the invention will be understood from the accompanying drawing and the following description and claims:—

In the drawing, Fig. 1 is a top plan view of a single unit structure, including a plurality of coil springs arranged in row formation and embodying the invention.

Fig. 2 is a top plan view of a corner of a composite spring structure, wherein the springs are arranged in longitudinal and transverse rows, and the longitudinal rows are associated together, the springs in each longitudinal row being in transverse alignment with the adjacent springs in the other adjacent longitudinal rows.

Fig. 3 is a view similar to Fig. 2, but the springs in alternate longitudinal rows are arranged in 85 transverse alignment and the springs in the successive transverse rows and alternate longitudinal rows are spaced apart both longitudinally and transversely by the springs in the intermediate longitudinal rows.

90 Fig. 4 is a side elevation of the unit shown in Fig. 1, embodying four helix means.

Fig. 5 is a similar view of a modified form of the invention shown in Figs. 1 and 4, and wherein in but two diametrically positioned helix means 95 are employed, and represents the minimum requirements for a spring unit construction embodying the invention.

In Figs. 1 and 4 of the drawing, 10 indicates a coil spring having the end turn 11 and the next immediate turn 12. The end turn 11 of the coil spring has a free end 13 which is provided with a serpentine formation 14 consisting of a series of undulations. The next immediate turn 12 has its portion adjacent the serpentine portion 14 105 similarly provided with a serpentine formation 15, the two serpentine portions nesting together and being united by an encircling small bore helix 16.

110 The portion of the end turn 11 substantially

opposite the serpentine portion 14, is similarly provided with a serpentine formation 17 and a small bore helix 18 is operatively associated therewith.

- 5 As shown in Fig. 4, there are two helices 16 provided and also two helices 18 are provided, and these are diametrically arranged with respect to the coil spring. Also, as shown in Fig. 4, the free ends 13 of the coil spring are diametrically positioned with respect to each other.

As shown in Fig. 1, each unit includes a plurality of coil springs arranged in spaced relation and preferably all of the free ends are in longitudinal alignment. When the free ends are in longitudinal alignment at the top and bottom of the unit and are diametrically opposite each other, then but two helices 16 are necessary to simultaneously secure the several spring portions together to form the equivalent of a knotted spring 10 and to secure said several springs together in single row formation and in spaced relation with each other in the row for unit spring construction. The same reference numerals have been intentionally applied to Figs. 4 and 5. If desired, the form of the spring utilized in Fig. 5 construction need not include the serpentine portion 17 in the end coil. In Fig. 5 but two helices 16 are required.

Whenever a multiple row spring construction is desired, as for bed springs and the like—see Fig. 2—the springs 110 are arranged in horizontal and transverse row formation. Each spring also has its end turn provided with a serpentine free end 114 and the adjacent portion of the immediate adjacent turn of said spring is provided with the nesting serpentine portion 115. The adjacent portion of the adjacent coil in the adjacent longitudinal row is provided with the serpentine portion 117 which also nests with the two other nesting portions of the adjacent coil in the first mentioned longitudinal row, making three nested serpentine portions which are encircled by the single helix 116.

A border wire consisting of the small bore helix 118 is operatively associated with the serpentine portions 117 of the end turn of the end coils of the longitudinal end rows of coils. A transverse border wire 120 consists of the small bore helix, as shown.

40 In the form of the invention shown in Fig. 2, the coils are arranged in longitudinal and transverse rows and the adjacent coils of each transverse row are in included adjacent longitudinal rows.

45 In Fig. 3, a modified form of the invention is illustrated, wherein the coils are arranged in longitudinal rows and are also arranged in transverse rows, the coils in each successive transverse row consisting of coils in alternate longitudinal rows, whereby an offset or staggered coil arrangement is obtained. The coils in respective longitudinal rows in this form of the invention are substantially arranged as in Fig. 1, the intermediate or spacing portion of the helix 216, and herein indicated as 221, being operatively associated and in effect, being the equivalent of the helix 18 of a single longitudinal row. The intermediate longitudinally arranged helices 216, therefore, in this form 50 of the invention, connect the coils of adjacent longitudinal rows in offset or staggered relation, while the intermediate longitudinal helices 116 of Fig. 2 connect the coils of longitudinal rows in transverse row arrangement, and each helix 116 in the form of the invention shown

in Fig. 2, operatively connects serpentine portions of coils in adjacent longitudinal rows in nested relation.

55 In Fig. 3, the numeral 218 indicates the small bore helix that serves as a border wire. Also 80 the numeral 220 indicates a small bore helix that serves as a transverse border wire. If desired, an intermediate portion between the two serpentine portions 114 and 117 of the coil 110, shown in Fig. 2, and operatively associated with the 85 border helix 120, may also be arranged in serpentine formation. Likewise, the coil 210 in Fig. 3, having the free end 213 provided with a serpentine portion 214, and the diametrically opposite serpentine portion 217 may have its intermediate portion similarly formed in serpentine formation for cooperation with the border forming helix 220.

90 In Fig. 3 each second turn of the coil 210 has its portion immediately adjacent the serpentine portion 214 of a serpentine formation 215 which nests with the serpentine portion 214 of the free end and the two are secured together in nested relation by the helix 216.

95 With respect to the modification last mentioned wherein the intermediate transverse portion between the serpentine portions 114 and 117, and 214 and 217, it is noted that a special border spring must be provided that differs from the majority of the springs embodied in the 100 spring structure as a whole. However, such additional transverse intermediate modification to the serpentine formation is not necessary and preferably is omitted for production purposes, since all the springs, with the exception of the 105 form illustrated in Fig. 5, are identical and may be used for single unit construction, or for multiple and transverse row arrangement, as shown in either Figs. 2 or 3, and may be employed for end coils as well as intermediate coils.

110 While the invention has been described in great detail in the foregoing specification and many modifications have been illustrated and described, the same is to be considered as illustrative and not restrictive in character, and such 115 modifications, as well as others which will readily suggest themselves to persons skilled in this art, are all to be considered within the scope of this invention, reference being had to the appended claims.

120 The invention claimed is:—

1. In a spring construction, the combination of a plurality of normally unknotted coiled springs arranged in a row and in spaced relation, each opposite end turn thereof having its 125 end provided with a serpentine portion consisting of a series of undulations, and the turn immediately adjacent thereto having an adjacent similar serpentine portion, said adjacent serpentine portions in each coil having a nesting 130 relationship, and a plurality of small bore helix means encircling the nested serpentine portions simultaneously securing the same together and the several springs in spaced relation and in row formation, whereby certain of said helix 135 means have a plurality of successive turns operatively associated with the successive nested undulations of the same spring.

140 2. In a spring construction, the combination of a plurality of normally unknotted coiled springs 145 arranged in a plurality of parallel rows, the springs in each row being arranged in spaced relation, each opposite end turn of each spring having its end provided with a serpentine portion consisting of a series of undulations, and the 150

turn immediately adjacent thereto in each coil having a similar adjacent serpentine portion nested therewith, each end turn substantially opposite the end serpentine portion having a similar serpentine portion therein, and a plurality of small bore helix means arranged in parallel relation and operatively associated with the ser-

pentine portions for securing said coil springs in spaced relation in the rows, whereby certain of said helix means have a plurality of successive turns encircling the successive nested undulations of the same spring.
